T. MAEZ

AMUSEMENT DEVICE

Filed Jan. 26, 1925

INVENTOR

Theodore Maez

BY *John H. Schaff*
ATTORNEY

UNITED STATES PATENT OFFICE.

THEODORE MAEZ, OF DURANGO, COLORADO.

AMUSEMENT DEVICE.

Application filed January 26, 1925. Serial No. 4,642.

This invention relates to toys or amusement devices having more particular reference to a device of the type in which a mannikin or like figure has certain parts thereof adapted for movement through the medium of springs controlled or manipulated by an operator, the invention having for an object the provision of a novel toy or amusement device of this sort.

For further comprehension of the invention, and of the objects and advantages thereof, reference will be had to the following description and accompanying drawing and to the appended claims in which the various novel features of the invention are more particularly set forth.

Fig. 1 of the drawing is a side view of my improved device showing the supporting platforms in section.

Fig. 2 is an end view of the device.

Fig. 3 is a face view showing the device as mounted behind the window of a house.

Fig. 4 is a side view showing a modified form of the device.

As here shown my improved device comprises a mannikin 10 which I have here shown as lying on its back on a platform 10'. The legs of the mannikin are shown at 11 and the arms at 12. In the normal operating arrangement of the parts these legs and arms extend upward substantially at right angles to the body. The arms may be fixed to the body to be permanently extended away from the latter, while the legs are here shown as pivotally attached to the body, being fixed on the opposite ends of a hinge rod 14 which is supported in the body of the mannikin and which has coiled therearound a spring

15 which is connected at one end to one of the legs and at opposite ends to the body and serves to retain the legs in their upright position. A stop 16' may be provided on the body to form an abutment for the legs when in upright position. The legs have connected to the ends thereof the cords 16, while the arms have connected to the ends thereof the cords 17. These cords 16 and 17 pass individually through a series of transverse openings 18 formed in and spaced along a bar 19 which the mannikin

is supposed to manipulate after the fashion of a juggler. The cords 16 from the legs connect at their ends to opposite ends of a handle-bar 21 while the cords 17 from the arms connect to opposite ends of a like han-

dle-bar 22. The head 24 of the mannikin may be pivotally attached thereto as at 25 to swing vertically and has connected thereto a cord 26 which extends upward and is attached to a foot pedal 27 mounted on a floor or platform 28 on which the operator stands. Projecting from one of the legs 11 is a lug or finger 30 to which is connected one end of a cord 31 which passes downward therefrom and around suitable pulleys 32 and finally upward to connect at its other end to the pedal 27.

In Fig. 1 of the drawing I have shown the bar 19 in position resting upon the feet of the mannikin, the cords 17 from the arms 12 being loosened, and the cords 16 from the legs 11 being tightened. By simultaneously moving the handle-bar 22 upward and the bar 21 downward and thereby tightening the cords 17 and loosening the cords 16 the bar 19 may be caused to travel from the feet to the hands of the mannikin, being indicated in the latter position in dot and dash lines in Fig. 1. By again tightening the cords 16 and loosening the cords 17 the bar may be caused to move back to position resting upon the feet of the mannikin or figure.

In Fig. 3 of the drawing I have indicated the device as mounted behind the window 34 of a house 35. In Fig. 4 of the drawing I have shown a modified construction in which the head 40 of the mannikin is loose on the body 41 and is formed with a vertical aperture 42 through which pass a pair of cords 43 and 44 one of which is attached at one end to the neck of the mannikin and the other to the end of one of the legs thereof, these cords being attached at their other ends to the handle-bars 45 and 46 respectively, the leg to which the said cord is attached being extended horizontally in front of the body. By the same process of simultaneously tightening one cord and loosening the other the head 40 may be caused to travel between its normal position and a position resting on the foot to which the cord is attached.

Having thus described my invention what I claim as new and desire to protect by Letters Patent of the United States is as follows:

1. A device of the class described comprising a toy figure, an element related to said figure and formed with spaced apertures adapted to be transferred between and rest freely upon different parts of said figure,

and individual cords passed freely through the apertures of said element and being attached at one end to the respective parts of the figure.

- 5 2. A device of the class described comprising a toy figure, an element related to said figure and formed with spaced apertures adapted to be transferred between and rest freely upon different parts of said figure, and individual cords passed freely through the apertures of said element and being attached at one end to the respective parts of the figure, and handles attached to the opposite ends of the cords.
- 15 3. A device of the class described comprising a figure, a bar formed with spaced apertures adapted to be passed between positions resting on the legs and arms of said figure respectively, pairs of cords connected at one end to the said legs and arms and passing through said apertures in said bar, and handle bars to opposite ends of which the other ends of the respective cords of each pair are attached, said legs being pivotally mounted on the body for swinging movement.

- 25 4. A device of the class described comprising a figure, a bar formed with spaced ap-

tures adapted to be passed between positions resting on the legs and arms of said figure respectively, pairs of cords connected at one end to the said legs and arms and passing through said apertures in said bar, and handle bars to opposite ends of which the other ends of the respective cords of each pair are attached, said legs being pivotally mounted on the body for swinging movement.

35 5. A device of the class described comprising a figure, a bar formed with spaced apertures adapted to be passed between positions resting on the legs and arms of said figure respectively, pairs of cords connected at one end to the said legs and arms and passing through said apertures in said bar, and handle bars to opposite ends of which the other ends of the respective cords of each pair are attached, said figure having the head and legs pivotally mounted on the body for swinging movement, and a common operating means for swinging said head and legs.

In testimony whereof I have affixed my signature.

THEODORE MAEZ.
